UNITED STATES PATENT OFFICE

WALTER H. FLOOD, OF CHICAGO, ILLINOIS

BUILDING UNIT AND SECURING MEANS THEREFOR

Application filed April 24, 1926. Serial No. 104,431.

This invention relates to building units and more particularly to securing clips therefor, although certain features thereof may be used with equal advantage for other purposes.

5 It contemplates more especially the provision of a single clip which may be interposed between two adjacent members to assemble them in rigid relation, whereby a structure of any design or contour may be 10 constructed and dismantled with ease.

In building units, especially those designed and constructed for recreational purposes, it is desirable to provide standard units of any suitable form which bear a relation to each

15 other to facilitate the assemblage thereof so as to produce with ease, a structure of any desirable or fanciful design. To arrange and maintain the units in their desired relation, it is essential or at least highly desirable to

20 provide simple and effective securing means which will enable a change in position of the units constituting the structure in order to make possible a change in design or permit an addition thereto without impairing their

25 sight or usefulness, thereby rendering them satisfactory for repeated use and for other amusement purposes to suit one's individual fancy.

One object of the present invention is to 30 provide an inexpensive and improved device of the character mentioned.

Another object is to provide improved securing means which can be readily interposed between adjacent members to maintain them 35 in aligned relation.

A further object is to provide improved means of inexpensive construction to facilitate repeated assembling or dismantling of related units without impairing their utility 40 or marring their surface.

A still further object is to provide related units of inexpensive construction which can be assembled with ease by employing a simple and effective securing means capable of 45 association therewith to produce a diminutive structure to simulate an object of any desired design or contour.

Other objects and advantages will appear 50 from the following description of an illus-

trated embodiment of the present invention.

In the drawings:

Figure 1 is a plan view of a securing member or clip embodying features of the present invention.

55 Figure 2 is a perspective view of a clip similar to the one shown in Figure 1, wherein it is bent along a median line $a-a$ to present a corner securing means of any desired angularity.

60 Figure 3 is a view in elevation showing the manner in which the clip illustrated in Figure 1, is applied to a unit which is to be aligned with an adjacent unit not shown.

65 Figure 4 is a perspective view of a structure comprising individual units in assembled relation having securing means interposed therebetween to maintain them in the desired relation.

70 Figure 5 is a sectional view taken substantially along the line 5-5 of Figure 4.

Figure 6 is a view in elevation of an individual unit constituting a part of a structure to be assembled.

75 The structure selected for illustration comprises a plurality of diminutive individual units 10 having any desirable configurations thereon, in this instance, doors or windows or both, which are related to each other so as to simulate in their assembled relation, a 80 structure of any desired design and contour, as for instance the house illustrated in Figure 4 which is provided with a roof 11 of any appropriate form.

85 In order to facilitate the assembly of the units with ease and without marring their surface in any way, they are selectively maintained in any desired relation by means of suitable fasteners or clips. The clips, in this instance, comprise a substantially flat member 12 composed of any suitable sheet material, such as celluloid, metal, paper and the like, from which is punched or struck a plurality of opposed tangs 13 and 14, preferably provided at spaced intervals along a 90 median line thereof as line $a-a$.

95 As shown, the tangs 13 and 14 are bent normal to the plane of the member as at 15 for a distance approximately equal to or slightly less than the thickness of the units 10, which 100

are received thereby in embracing relation by virtue of the portion 16 extending parallel to the base of the clip 12 in integral relation therewith to present a resilient L-shaped tang. The apertures 17 in the member 12 obviously correspond in size with their respective tangs removed therefrom. These apertures are concealed from view when the sections are in assembled position with the units 10 associated therewith.

To facilitate the assembly of angularly related units, it is only necessary to bend the member 12 along a median line thereof, as for instance along line $a-a$, to present the desired angular relation between the parts thereof. It is to be noted that the portion of the tang normal to its base, in this instance, will necessarily be somewhat longer than the same portion in the form previously described to compensate for the distance b shown in Figures 1 and 2. It is evident that any number of series of opposed tangs, in this instance two, may be employed depending largely upon the nature and size of the structure to be assembled.

With the arrangement of parts above described, it is obvious that adjacent units can be conveniently assembled and dismantled by merely introducing the clip 12 between the adjacent edges of the units so that the base thereof will contact with the inner sides thereof with the portion 15 of the tang intermediate the adjacent edges in resilient frictional engagement therewith owing to the portion 16 which contacts with the outer side of the units 10 to maintain them in their desired aligned relation. The clip is preferably removed by sliding it along the joint formed by the adjacent members whence it is removed from the end thereof.

Various changes may be made in the embodiment of the invention hereinabove specifically described, without departing from or sacrificing any of the advantages of the invention as defined in the appended claim.

I claim:

An attaching plate adapted to connect adjacent members, said plate having a series of struck-up tangs extending transversely thereof in spaced-apart relation lengthwise of the plate, each tang having at its inner end a portion normal to the plate, said tangs extending in alternately opposite directions and having their said inner end portions upon alternately opposite sides of the longitudinal median line of the plate and their body portions offset laterally in alternating relation and the inner end of each tang being positioned closely adjacent to the longitudinal median line of the plate so as to connect the adjacent members in edgewise abutting relation.

In testimony whereof I have hereunto subscribed my name.

65 WALTER H. FLOOD.
